(57) **CLAIM**

The ornamental design for a hand pillow, as shown and described.

DESCRIPTION

FIG. 1 is a perspective view of the hand pillow of the instant invention;

FIG. 2 is a view of the hand pillow in a state of use;

FIG. 3 is a left side view thereof, the right side view forming a mirror image; and,

FIG. 4 is a first end view thereof, the opposite end forming a mirror image.

The broken lines represent environmental subject matter and form no part of the claimed design.
